DESIGN FOR A SHOE OR SIMILAR ARTICLE

Samuel L. Kleven, Augusta, Maine

Application December 31, 1943, Serial No. 112,137

Term of patent 14 years

(Cl. D7—7)

To all whom it may concern:

Be it known that I, Samuel L. Kleven, a citizen of the United States, residing at Augusta, in the county of Kennebec, and State of Maine, have invented a new, original, and ornamental Design for a Shoe or Similar Article, of which the following is a specification, reference being had to the accompanying drawing, forming part thereof.

Fig. 1 is a side elevation of a shoe or similar article showing my new design, the opposite side presenting substantially the same appearance as the one shown.

Fig. 2 is a section on the line 2—2 of Fig. 1.

The characteristic features of my design for a shoe reside in the perforated trim of a contrasting color shown in full lines, in combination with the diagonal lacing joining the lower edge of the trim with the insole or platform member.

I claim:

The ornamental design for a shoe or similar article, substantially as shown and described.

SAM'L L. KLEVEN.
